UNITED STATES PATENT OFFICE.

GEORGE W. CRAM, OF LIBERTY, MAINE, AND ADDIE B. MOORE, OF LAWRENCE, MASSACHUSETTS, EXECUTORS OF ELIJAH W. CRAM, DECEASED.

TURBINE WATER-WHEEL.

SPECIFICATION forming part of Letters Patent No. 617,281, dated January 3, 1899.

Application filed March 25, 1898. Serial No. 675,173. (No model.)

To all whom it may concern:

Be it known that we, GEORGE W. CRAM, residing at Liberty, in the county of Waldo and State of Maine, and ADDIE B. MOORE, residing at Lawrence, in the county of Essex and State of Massachusetts, citizens of the United States, executors of the last will and testament of ELIJAH W. CRAM, deceased, late a citizen of the United States and a resident 10 at Liberty, Maine, who in his lifetime invented certain new and useful Improvements in Turbine Water-Wheels, do hereby declare the following to be a full, clear, and exact description of the invention, such as will enable 15 others skilled in the art to which it appertains to make and use the same.

The objects of this invention are to provide a turbine water-wheel which shall be constructed in such manner as to utilize the highest possible percentage of power and at the same time to minimize frictional resistance and consequent loss of power; furthermore, to present a novel form of bucket the construction of which shall be such as to cause 25 the water to be discharged in three different directions in one whole unbroken sheet, and, finally, to assemble the buckets and the head-block or crown-plate in such manner that the buckets at their points of junction with the 30 head-block will be rigidly held in place and at their points of assemblage with each other will be held positively against lateral bulge or strain in use.

With these objects in view the invention 35 consists in the novel construction and combination of parts of a water-wheel, as will be hereinafter fully described and claimed.

In the accompanying drawings, forming a part of this specification, and in which like 40 letters of reference indicate corresponding parts, there is illustrated one form of embodiment of the invention, it being understood that other forms of embodiment may be employed without departing from the spirit of 45 the same, and in which—

Figure 1 is a view in side elevation of a complete wheel. Fig. 2 is a view in elevation, partly in section, showing the manner in which the buckets are assembled with relation to the

head-block or crown-plate. Fig. 3 is a view 50 in plan, partly in section, of the bottom of the wheel, looking upward. Fig. 4 is a view in perspective of one of the buckets detached from the wheel. Fig. 5 is a view in perspective, showing the manner in which the buckets are 55 connected by a lap-joint. Fig. 6 is a fragmentary section taken on the line 6 6, Fig. 4. Fig. 7 is a transverse sectional view taken on the line 7 7, Fig. 4, showing the peculiar shape 60 of the bucket.

Referring to the drawings, A designates the head-block or crown-plate, B the buckets, and B² the blades of the buckets, the buckets and the blades being by preference cast integral. 65

The head-block comprises a base a and a conical hub, as usual, to which latter the upper ends of the blades of the buckets are secured, as by being riveted thereto or cast integral therewith, as may be preferred. The 70 hub a² is made a true bevel instead of a concave for the reason that the water instantly begins to lift on the head-block when it takes hold of the buckets, thereby causing the wheel to run easily and bear but lightly upon the 75 step C. The periphery of the head-block is provided with a downturned rim a³ and the base with a boss or extension a⁴, constituting a bearing-surface, the walls of the periphery of the latter extending parallel with the 80 axis of the shaft D. As will be seen by reference to Fig. 1, the upper end of the blade of each bucket is formed into a compound curve and is provided with laterally-extending lips b, forming a continuous flange on 85 each side of the blade from edge to edge, and these lips are adapted to bear against the hub, so as to present a broad bearing-surface to be impinged by or inclosed with the metal of the head, as in assembling the parts, as 90 before stated, the buckets and blades may be cast integral with the head-block or be riveted thereto. The upper end of the outer edge of the blade is cut away to form an angular point, as at b², and this point is adapted 95 to fit under the overhanging rim a³ of the head-block, so that movement of the blades from the shaft at these points will be obvi-

ated, thereby preventing strain at the points where the buckets are attached to the head-block, while the periphery of the boss a^4 , against which the blades also bear, will further assist in holding the blades rigid. It will be seen from this description that the buckets and blades are secured to the head-block and are held against displacement by strain at three points—namely, at the hub, 10 at the points b^2 , and at the points a^4 . As stated, the upper end of each blade where the lips b are provided forms a compound curve, and this is caused by the peculiar shape of the blade in cross-section, as shown 15 in Fig. 7, so that in order to get a close and firm union between the hub and the upper end of the blade it will be necessary to form the said end on this peculiar curve. Otherwise the desired union could not be effected.

20 The upper outer edge of the bucket is formed into the arc of a circle, and extending the entire length of this arc is a lip or flange b^3 , which when the buckets are assembled with relation to the head-block forms a 25 circumferential flange or seat for a band or collar E for holding the buckets rigidly in position against lateral spread or displacement, as from entrance of debris in the nature of stones or the like into the buckets. At the 30 rear portion of this flange is a depression b^4 , terminating in a V-shaped recess b^5 , and at the forward portion is a projection b^6 to engage the recess b^5 of the preceding bucket to form a lap-joint.

35 The shape of the bucket is the result of a great number of experiments and careful study and may be described generally as combining the following angles and curves: The slight curve of the blade formed at the entrance edge of the bucket from 1 to 2 and arranged approximately at right angles to the shaft, thereby presenting the least resistance to the entrance of water, the rear sharp outward curve from 2 to 3 formed at the rear of 45 the bucket and serving to effect the rapid discharge of the water, thereby obviating any retardation in the operation of the wheel, and the curve of the upper edge of the outer face of the bucket from the rear edge of the blade 50 outward to the front edge thereof in the arc of a circle, as shown at 4, Fig. 4, and disposed so as to give a relatively large entrance-mouth and a relatively large discharge-mouth, thereby also assisting in the rapid discharge of the 55 water. These angles and curves have all been computed with nicety, and while their exact proportions are not herein stated it has been found that the result attained is the generation of the highest possible power from 60 a given force of water with a minimum resistance to discharge.

By the peculiar arrangement of the lap-joint described in connection with the buckets these may be assembled in such manner that 65 lateral displacement is practically impossible, and by the addition of the band or collar E ,

which may be shrunk or otherwise secured to the flanges, separation of the lap-joints is positively obviated.

The buckets constructed in the manner described give four distinct actions to the water, the first being a direct plunge from the chutes, the second a direct pressure at an angle leading toward the center, the third a gravity-pressure, which is greatly augmented by the water rushing under the beveled face of the head-block and crowding down on the vertical sections of the buckets, and the fourth a pressure on the curved surface in the outer wing of the bucket tangential to the center of the wheel, which latter action is greatly increased by centrifugal force when the wheel is in motion. These combined actions of the water enable the wheel to discharge the water in three different directions in one whole unbroken sheet.

In assembling the wheel the blades are first placed in proper position with relation to each other in a mold, and the head-block is then cast thereon, causing the lips b , and with them the buckets or blades, to become an integral part of the head-block. It is to be understood, however, that the invention is not to be limited to this particular manner of assembling the blades with the head-block, as these lips may be made of sufficient width to admit of their being riveted or otherwise secured to the head-block.

Having thus fully described the invention, what is claimed as new, and desired to be secured by Letters Patent of the United States, is—

1. A turbine water-wheel comprising a head-block and a plurality of buckets, each bucket being provided with an upward-extending flange, the rear portion of the flange being provided with a recess, and the front portion with a projection, substantially as described.

2. A turbine water-wheel comprising a head-block and a plurality of buckets rigidly connected therewith, each bucket being provided with an upward-extending flange, the rear portion of the flange having a recess, and the front portion a projection adapted to engage a similar recess in the next succeeding bucket, to constitute a lap-joint, and a band or collar inclosing the flanges of the continuous series of lap-joints, substantially as described.

3. In a water-wheel, a head-block having a conical hub terminating at its lower portion in a boss having straight walls, and the upper edge of the head-block being formed into an overhanging rim, in combination with buckets having their blade portions secured against the hub and engaging the said boss and rim, the outer wing of the buckets being drawn in at the top to form arcs of circles arranged tangential to the circumference of the head-block, the said buckets being each provided with an upward-extending flange, the

rear portion of which is provided with a recess, and the front portion with a projection extending beyond the bucket and adapted to engage a recess in the flange of the next succeeding bucket, to constitute a lap-joint, and a band or collar inclosing the flanges of the continuous series of lap-joints, substantially as described.

4. As a new article of manufacture, a bucket for turbine water-wheels, comprising a blade and a bucket, the bucket being provided with an upward-extending flange, the rear portion of which is provided with a recess, and the front portion with a projection, substantially as described.

In testimony whereof we affix our signatures in presence of two witnesses.
